UNITED STATES PATENT OFFICE.

WALTER C. HORINE, OF ARROWSMITH, ILLINOIS.

CORN-CONVEYER.

SPECIFICATION forming part of Letters Patent No. 663,276, dated December 4, 1900.

Application filed March 16, 1900. Serial No. 8,943. (No model.)

To all whom it may concern:

Be it known that I, WALTER C. HORINE, a citizen of the United States, residing at Arrowsmith, in the county of McLean and State 5 of Illinois, have invented certain new and useful Improvements in Corn-Conveyers; and I do hereby declare the following to be a full, clear, and exact description of the invention, such as will enable others skilled in the art to 10 to which it appertains to make and use the same.

My invention relates to certain improvements in what may be termed "corn-conveyers," adapted for use more especially in connection with shellers.

15 It has for its object to promote convenience in the arrangement of the conveyer with relation to the corn-crib and the sheller, to provide for readily supporting the conveyer in position without other or additional means 20 than the ground, to dispense with such additional means as heretofore employed therefor, to greatly simplify construction and therefore lessen the cost of manufacture, and to otherwise improve the construction and arrangement 25 of the parts of the device.

It consists principally of a feeder-hinged section or extension and a conveyer, together with mechanism for actuating the endless chains or belts arranged in the respective 30 sections of the conveyer from the sheller or other suitable means for imparting motion thereto or driving the same, and of certain details of construction and combinations of parts, substantially as hereinafter more fully 35 disclosed, and specifically pointed out by the claims.

It will be understood that latitude is allowed herein as to details, as they may be changed or varied at pleasure, according to 40 circumstances, without departing from the spirit of my invention and the same yet remain intact and be protected.

In the accompanying drawings, illustrating the preferred embodiment of my invention, 45 Figure 1 is a perspective view of sufficient of a corn-sheller looking toward its receiving or feeding end to show the application of the invention thereto with the hinged section of the feeder folded back out of use. Fig. 2 is 50 an enlarged detail view of an endless chain or belt shaft and intergeared shafts. Fig. 3 is a broken-away sectional view disclosing an

endless chain or belt of the hinged section of the sheller-feeder. Fig. 4 is a perspective view of the conveyer in sections as arranged 55 in position with relation to said feeder. Fig. 5 is a side view of the tumbling or driving shaft and the gearing between it and a conveyer endless chain or belt shaft. Fig. 6 is a detailed view of a belt-tightener applied to 60 a belt compassing sprocket-wheels or pulleys on shafts of sections of the conveyer. Fig. 7 is a broken detailed side view disclosing more particularly an angular terminal of a belt-shaft to which the driving-shaft is applied when the conveyer sections or troughs 65 are arranged at an angle to the corn-sheller feeder. Fig. 8 is a plan view showing the corn-sheller feeder and conveyer-sections arranged in alinement, with the latter, also 70 shown in dotted lines, disposed or deflected somewhat at an angle or out of alinement with the feeder. Fig. 9 is a side elevation thereof, parts being broken away. Fig. 10 is a broken plan view showing more particularly the lower part of the corn-sheller feeder and a portion of a corn-conveyer section, the same being arranged or disposed at right angles to each other. Fig. 11 is a detailed view 75 showing more particularly the guard or arrester to prevent the falling or rolling of the corn back under the endless belt or carrier therefor.

In carrying out my invention I provide a conveyer comprising a requisite or suitable 85 number of sections 1 1, preferably in the form of troughs. These are preferably provided with upper edge divergent boards or guards 1^a 1^a to insure the falling of the ear-corn into said troughs as the attendant shovels 90 or pushes it from the corn-crib, alongside of which one of said conveyer sections or troughs is disposed or arranged. The conveyer sections or troughs 1 1 are provided with suitable endless chain belts 2 2, having 95 "flights" or blades to engage and carry the corn along said conveyer-sections and finally deliver it to the hopper of the hinged section or extension 3 of the feeder 4 of the sheller presently described. The shafts 5 of the pulleys or sprocket-wheels 6, around which pass said chains or belts 2, bear in the sides of said conveyer sections or brackets attached thereto. The projecting ends of adjacent shafts 100

of the conveyer-sections are provided with outside sprocket-wheels or pulleys 7 compassed by a belt 8 to transmit motion from one corn-carrying belt to the other belt.

5 The belt 8 is adapted to be tightened by means of a tightener 9 of any ordinary or approved construction and suitably hung in position upon the side of the conveyer-section.

10 A pin or bolt 10, with its upper suitably constructed or enlarged angular end fastened to the side of one conveyer-section, is adapted to enter or engage an eye or staple 11, suitably secured to the side of the other conveyer-section just below or in vertical alinement with said bolt, to connect said conveyer-sections, and to provide for readily disposing or arranging the required conveyer-section with relation to the corn-crib, as circumstances 15 20 may make it necessary, as will be readily understood.

As above intimated, I provide the corn-sheller-feeder 4 with a hinged section 3, adapted in all respects to constitute or form a continuation or extension of said feeder and preferably adapted to reach down to and rest upon the ground or close thereto, its extreme lower end being provided with a hopper 14 or adapted to have placed therein such, the 25 30 purpose of which has been before referred to. Said hinged section or extension of the feeder has arranged in its lower end a shaft 15, provided with sprocket-wheels or pulleys 16, compassed by the lower portion of the endless chain or belt 17 of the feeder 4. Said belt or chain carries transverse edgewise-arranged pieces or flights 18 to engage and elevate the corn delivered into said hinged section or extension of the sheller-feeder from the conveyer aforesaid. Also arranged in the lower end of said hinged section or extension is an edgewise-disposed plate 19, which, together with a cross piece or bar 19^x suitably suspended in position in said hinged section, 35 40 forms an arrester or guard adapted to prevent the corn being elevated by the belt or its flights from falling or rolling back under the latter accidentally. Said plate has formed integrally therewith a spring arm or 45 50 extension 19^a, extending from its lower edge and preferably curved or bowed upward, as shown, and having its outer end or edge bent into tubular form to receive a rod or pivot 19^b, secured in the sides of said hinged section. Said guard or plate 19 is thus adapted 55 60 not only to normally rest upon the belt, but by reason of its springy character and being pivoted it will sufficiently rebound to prevent undue hammering of the belt and yet not be displaced or its efficiency interfered with. Said plate is thus held automatically down upon the belt or chain of said hinged section and will rearwardly yield upward as the flights pass thereunder and consequently automatically resume its normal position under the action of its spring. Outward or rearward displacement of the cross-bar 19^x is pre-

vented by cleats or projections 20 relatively arranged therewith and suitably secured at the sides of said hinged section or extension. 70

In order to drive the endless chains or belts 2 of the corn-conveyers, I provide, preferably, a tumbling-rod shaft 21 in longitudinally sliding or extensible sections 21^a 21^b, suitably splined together, as shown, or otherwise against independent axial movement or turning. Said rod or shaft sections are connected to the driving-gear of the sheller and to the conveyer-belt gearing, respectively, by universal couplings or joints 22 23, each comprising a ring 23^a, one of two half-circle forks 24 on the outer ends of the shaft-sections, respectively, and one of two half circles or forks 25 on the ends of socket-pieces 26, one adapted to receive one of two bevel gear-shafts 27 80 85 16 of said belt and sheller gearing, respectively. These half circles or forks 24 25 are connected or pivoted to the ring 23^a at points in lines passing through or intersecting each other at right angles, whereby said sectional 90 shaft 21 may readily accommodate itself to different angular presentations or positions with relation to the sheller, thus providing for like relative arrangement or placing of the conveyer-sections, as disclosed in one figure of the drawings. The conveyer-sections 95 may also be disposed or arranged in substantial alinement with the feeder of the sheller, according as circumstances may require. When the conveyer is arranged at an angle 100 to the feeder of the corn-sheller, as shown in Fig. 1, the bevel-gearing is dispensed with and the driving-shaft directly connected or coupled to the angular terminals 29 of the endless-belt pulley-shaft. By means of the foregoing also the conveyer-belts may be driven from either side, as may be required, for greater convenience or of necessity. 105

When the apparatus or device is not in use, the hinged section or extension may be folded 110 up under the feeder of the sheller out of the way, as shown, thus economizing room or space and housing the same, as it were, for convenience in transporting the machine along the road or elsewhere. 115

It will be observed that by means of this device or apparatus it is not necessary to suspend the conveyer-sections and the corn-sheller feeder when feeding the corn to the sheller in an elevated position, and consequently provide additional means or facilities therefor, the conveyer-sections, together with the feeder, in my apparatus being adapted to rest upon the ground, and said conveyer-sections adapted to deliver their contents into 120 125 the corn-sheller feeder through the medium of the hinged section or extension, as before stated.

Having thus fully described my invention, what I claim, and desire to secure by Letters 130 Patent, is—

1. In apparatus of the character described, the feeder for a corn-sheller, &c., comprising a lower hinged section or extension and an

- endless carrying-belt, a conveyer adapted to deliver into said lower hinged section or extension, and a guard or arrester comprising a suspended cross piece or bar, cleats or projections adapted to engage and prevent rearward displacement of said cross piece or bar, and a spring-supported plate arranged contiguously to, and in rear of, said cross piece or bar, substantially as specified.
2. In apparatus of the character described, a corn-sheller and its feeder comprising pulleys or wheels, and endless carrying-belts compassing said pulleys or wheels, one of the shafts of said pulleys or wheels having a bevel-faced pinion and an angular terminal, the corn-sheller gear, and a driving or tumbling shaft having a pinion adapted to mesh with said bevel-faced pinion and an angular socket adapted to engage said angular terminal, said shaft also adapted to engage said
- corn - sheller gearing, substantially as set forth.
3. In apparatus of the character described, a corn-sheller with its gearing, and a feeder, comprising an upper main section and a lower folding section, and an endless carrier arranged in said feeder-sections, means for carrying said folding section, a conveyer having an endless carrier, and gearing for driving said carrier, said conveyer delivering into said folding section, and tumbling rod or shaft mechanism adapted to actuate the corn-sheller gearing and the endless carrier-gearing, substantially as set forth.
- In testimony whereof I affix my signature in presence of two witnesses.
- W. C. HORINE.
